[57] CLAIM

The ornamental design for an insulated bottle, as shown and described.

DESCRIPTION

FIG. 1 is a top, front and left side perspective view of an insulated bottle, showing my new design;

FIG. 2 is a front elevational view thereof;

FIG. 3 is a left side view thereof, the right side being a mirror image of the side shown;

FIG. 4 is a rear elevational view thereof;

FIG. 5 is a top plan view thereof, the bottom view being a mirror image of the top plan view shown; and,

FIG. 6 is a left side view thereof with a cap portion thereof being removed and the cap being shown in a partial fragmentary view.
